ELECTRIC BULB SOCKET

Charles Emory Wilson, Chicago, Ill.

Application February 8, 1936, Serial No. 63,032

2 Claims. (Cl. 240—10)

This invention relates particularly to a new electric bulb socket embodied in a new method and combination of devices for producing novel, useful, and pleasing decorative lighting effects.

5 In general terms the invention consists of an airtight electric lamp or bulb socket so constructed and shaped to fit the base contour of the electric bulb that no break of surface contour exists between electric bulb and socket.

10 The specific purpose of this airtight socket, its streamlined fitting to the light bulb, is to facilitate the insertion of the lamp bulb and a portion of the socket into and through the neck of a pre-inflated rubber semi-transparent balloon.

15 In the preferred exemplification of the invention, a rubber balloon having a neck opening about one-half the diameter of the greatest diameter of bulb and socket, is first inflated and then slipped over both bulb and socket until neck 20 of balloon comes in contact with the stop rim at end of socket opposite electric bulb, the tip of the bulb having previously been lubricated with a pure vegetable oil or grease which eliminates the friction within the rubber balloon neck as it passes over the bulb and the socket, during 25 the operation, and serves, with the contraction of the balloon neck upon the socket, to seal the inflating gas or air within the balloon.

The socket, the bulb and the balloon may be 30 varied in size and color, and the balloon used in a variety of shapes and may carry printed legends, pictures, etc. The principles of the invention will be better understood from the following detailed description of certain approved 35 embodiments of the invention.

In the accompanying drawings:

Figure 1 is an elevation of the external contour of this novel socket showing bulb and balloon neck in place after being mounted.

40 Figure 2 is an elevation showing a lateral cut section of the novel socket showing internal shaping and method of making an airtight socket with stranded wire conductors.

45 Figure 3 is an elevation showing a variation in manufacture whereby the female screw shell with conductor wires attached are molded into a solid rubber unit.

50 Figure 4 is an elevation showing an extension shaft molded as a unit with socket body for attaching socket to tube by inserting shaft within tube.

55 Figure 5 is an enlarged sketch showing method of preventing air leak through stranded wire conductor leads.

Figure 6 is an elevation of a series of electric

lighted balloons, illustrating the pendant style of mounting this novel socket.

Figure 7 is an elevation showing a modification in which stiff solid single wire conductors are employed to secure rigidity where the novel 5 socket is used in an upright position.

Figure 8 is a further modification showing socket attached to tube of paper, fiber or metal, with an enlarged chamber in the end of the tube for enclosing batteries which are connected 10 within the tube by individually insulated wire conductors to the novel socket.

Referring first to the form of the invention as shown in Figure 1. The assembly by way of example shows the body of the socket 1, the 15 lamp bulb 2, and the balloon neck 3, stop rim 4, and insulated conductor wires 5. A thin rubber balloon adapted to transmit light therethrough has a reduced neck portion through which the inflating medium is blown before being assembled over bulb and socket. Similar balloons heretofore known are held in inflated condition by clamping or tying the neck to prevent the escape of the inflating medium.

According to this invention the inflating me- 25 dium is sealed within the balloon by the contraction of the expanded neck portion upon the outer surface of the socket body without the use of other binding or expanding elements. The electric bulb 2, and socket 1, are pushed into and 30 through the neck 3, without obstruction until the farther progress of neck 3 is prevented by contact with the abrupt stop rim 4.

It will be easily understood that with the ex- 35 panded balloon neck 3 sliding along the circular surface from the tip of the bulb 2, over the larger portion of the bulb 2, that any substantial break or opening between bulb and socket 1, will allow the balloon neck 3, as it advances from bulb 2, to socket 1, to sink or contract into such 40 opening and impede its progress onto the socket 1. The close contact between socket 1 and bulb 2 eliminates this difficulty in this socket invention.

Furthermore, the absence of any rim, shoulder, hump, groove, abrasion, or obstruction along the 45 contour of socket 1 over which the balloon neck 3 advances, facilitates the movement of the balloon neck to stop rim 4. While this stop rim 4 is of sufficient height to act as a stop to the farther advance of the balloon neck 3, it is also 50 low enough to allow the thumb or finger when pushed across stop rim 4 toward the bulb, to contact the balloon neck 3, and start it rolling toward bulb 2 and on over bulb, in which way the balloon is removed from the assembly. The 55

absence of any rim, shoulder, hump, groove, abrasion or obstruction, as in mounting the balloon facilitates the unmounting or removal of the balloon from the assembly.

5 It will be noted in Figure 1, that the contour of the novel socket 1 has a gradual lateral reverse curve starting with a slightly convex curve near bulb 2 and changing to a more abrupt concave curve ending at stop rim 4, in which the balloon 10 neck 3 is held in repose when mounted. The concave curve is an aid in preventing the balloon neck 3 from slipping either toward the bulb 2 or upward over the stop rim. This curve also prevents balloon neck 3 from being pulled off socket 15 1 prematurely either by hand or wind. A pull on the inflated body of the balloon contracts the rubber at neck 3 and makes it grip socket 1 more tightly. With the convex curve against which the contracted neck binds when pulled, all danger 20 of balloon becoming unmounted prematurely is eliminated.

Figure 2 shows a split or lengthwise cross-section of this socket invention giving a lateral view of body of socket 1, standard female screw shell 25 14, conductor wires showing insulation 5, conductor wires showing insulation removed and each stranded wire soldered into a unit 6, concave cavity for light bulb base 7, and core opening 30 filled with filling compound 8. This sketch shows the internal assembly of the socket invention with the socket body 1 formed from extruded rubber straight stock with outside diameter and inside opening of proper size. On a mandrel it is cut and turned to shape externally, and with 35 a series of machine cutters it is shaped internally. The female screw shell 14 is inserted with friction. Rubber in composition known as "baby-carriage tire stock" is used for body 1, for the reason that it machines easily, is a perfect insulator, air leak proof, practically indestructible and sufficiently flexible to conform to the contour of any bulb which may vary in diameter or one that may be made with the screw shell base 40 mounted slightly off center. 45 Female screw shell 14 is standard in the various sizes from miniature to mogul size, and may be either flanged at the opening or plain. When flanged the flange fits snugly against the rubber body 1 at the inside terminus of cavity 50 1. Conductor wires 5 are stranded, flexible and insulated. This type wire is provided where the novel socket 1 is intended to be used in pendant position which permits the assembly to hang perpendicular of its own weight and permits swinging 55 in breeze or air-current without danger of breaking conductor wires 5. Insulation of conductor wires 5 is allowed to extend within the core opening 8 of body 1, so that it is cemented tight with the filling compound thereby preventing the slipping of the insulation and exposure 60 of bare conductor wires.

Conductor wires 6 within the body and connected to the female screw shell 14, while of stranded wire, have been made air tight by dipping them in molten solder before being attached to female screw shell 14. When core opening 8 in body 1 is filled with melted filling compound, the socket is complete.

Figure 3 shows a modification of the novel socket 1, being primarily a variation in mode of manufacture. Instead of using extruded pre-vulcanized rubber for body, as in Figure 2, this invention may be made by moulding the body 1 of rubber to shape and contour enclosing the conductor wires 6 and 5 and female screw shell 14

within a semisolid rubber body in accordance with common shop practice for moulded articles of this kind.

Figure 4 is a lengthwise cross-section showing a modification of socket invention, being primarily a variation in form of molded body 1, wherein an extension shaft or cylinder is molded as a unit with body 1. Conductor wires 5 with insulation are enclosed within the extension shaft which is held by compression within tube 12. The extension shaft or cylinder may be varied in all diameters within the outside diameter of stop rim 4 on socket 1. Variations in materials used for the body of this socket invention in any of its forms may include any material such as composition, wood, metal, rubber, synthetic rubber-bakelite, etc. and its method of manufacture may vary according to accepted shop practice for the various materials used.

Figure 5 is a cross-section showing the results obtained through the immersion of the stranded conductor wires in molten solder to close the minute interstices which would normally exist between a cluster of round stranded wires. Dipping the wire first into soldering liquid and then into melted solder reduces all the wires to a single unit 16 around which the filling compound may flow and contact.

Figure 6 illustrates a series of pendant assemblies. Feed wires 9 to which are attached conductor wires 5 support the socket, bulb and balloon 10 through its contact with socket 1. Size of all members may be varied also spacing on feed wire 9, length of conductor wire 5 and shape of balloon 10. Also this novel socket may be attached to all approved systems of wiring arrangements, parallel, series, etc.

Figure 7 is a modification of this novel socket wherein its embodied elements are identical with the exception that solid stiff conductor wires 11 are used at 5 and 6 in Figure 2, where stranded conductor wires are shown, to enable the novel socket to be used in an upright rather than a pendant position. The stiff conductor wires 11 supporting the novel socket, bulb, and pre-inflated balloon 10, through contact between neck 3 and socket body. Insulation 5 is cemented in side body 1, as shown in Figure 2.

Figure 8 is a further modification showing socket invention attached to tube 12 of paper, fiber or metal, by inserting tube into core opening 8, Figure 2. The novel socket in this case is connected by conductor wires within the tube to battery in chamber 13 at opposite end of tube, the bulb and pre-inflated balloon 10 supported by neck 3 on socket completing the lightable balloon wand or staff for being carried in the hand. A thumb switch flashes the light at will. All members may be varied in size and balloon 10 tube 12 and battery chamber 13 may be varied in form.

I claim

1. An airtight, valveless and ventless electric bulb socket having an outside unbroken lengthwise contour wherein a convex curve joins to a gradually increasing concave curve and terminates in a stop ring at the conductor end of the socket, said socket having a flexible extension forming a concave opening for snugly receiving an electric lamp bulb whereby the socket and bulb form an unbroken lengthwise contour.

2. The combination of a tapered incandescent electric bulb having a gradually increasing diameter from the tip to a point near the base, with an airtight, valveless and ventless electric bulb

socket which extends approximately from the greatest diameter of the bulb and is of such shape that the socket and bulb form an unbroken lengthwise contour which terminates at the end 5 of the socket in a concave curve and a stop ring, with a rubber balloon having an expansive neck

portion through which it is previously inflated, mounted over bulb and upon the concave portion of the socket and in contact with the stop ring whereby said inflated balloon neck is held stationary by its contracting tendency. 5

CHARLES EMORY WILSON.
